POWER PRESS CONTROL

Original Filed Jan. 7, 1925

3 Sheets-Sheet 3

UNITED STATES PATENT OFFICE.

ARTHUR A. BYERLEIN, OF DETROIT, MICHIGAN, ASSIGNOR TO THE HAMILTON PRESS & MACHINERY COMPANY, OF HAMILTON, OHIO, A CORPORATION OF OHIO.

POWER-PRESS CONTROL.

Original application filed January 7, 1925, Serial No. 1,018. Divided and this application filed June 11, 1927. Serial No. 198,297.

This invention relates to power presses and particularly to the control mechanism therefore, the present application being a division of my prior application Serial No. 1,018 filed 5 January 7, 1925 for power press control.

One of the principal objects of the present invention is to provide a power press with control mechanism so constructed that the press may be manually started and stopped 10 at any point in the cycle of operations of the press and which embodies means for returning the control member by which the manual control is effected to stopping position even if the operator should absent-mindedly hold 15 the lever in the "on" position.

Other objects and advantages of the invention will be apparent from the following description taken in connection with the accompanying drawings in which—

20 Fig. 1 is a front elevation of a portion of the press showing the control mechanism of the present invention;

Fig. 2 is a side elevation of the press;

25 Fig. 3 is an elevation of the trip mechanism forming part of the present invention;

Figs. 4 and 5 are sectional views with parts broken away, taken on the line 4—4 of Fig. 3 and showing different operating positions of the trip mechanism;

30 Fig. 6 is an exploded sectional view on the line 6—6 of Fig. 4; and

Fig. 7 is a detail view of the trip actuated member.

Referring to the drawings, 20 designates a 35 part of a power press which is provided with a slide member 21 slidably mounted in the side frame 22 and driven from the crank-shaft 23 to which it is connected by suitable means such as cranks 19 to impart a reciprocating 40 motion to the slide.

It will be understood that the general arrangement of the press is similar to the construction embodied in my copending application above referred to. In presses such as 45 are used for stamping metal the slide is generally operated intermittently, one complete cycle of operation consisting of a down-stroke of the slide followed by its up-stroke, the slide being brought to rest in an up position to permit the removal of the formed work and the insertion of a fresh blank. For the purpose of imparting such motion to the slide the press is provided with a driving member such as the continuously rotating shaft 24 to

which the crank-shaft may be connected from 55 time to time by means of a gear train including the gear 25 and the clutch 26. A brake-band 27 adapted to bear frictionally upon the outer surface of the clutch housing or casing 26 is provided to assist in arresting the rotation of the crank-shaft 23 at the proper predetermined point in the cycle of operations.

The clutch and the brake are controlled from the clutch control shaft 30 to which is keyed a lever 31, the lower portion of which 65 is formed as a yoke and is connected with clutch sleeve 32. The upper end of the lever 31 is connected through the link 33 to the joint between toggle links 34 and 34' so that movement of link 33 rocks the arm 35 to which the 70 upper toggle lever 34 is pivoted. Arm 35 is fast on the shaft which bears a second arm 35' connected at its end to rod 36' which is fastened to one end of the brake-band 27. The opposite end of the brake-band is fastened at 37' as shown in Fig. 2. The construction of the clutch is such that when the lever 31 is turned in a clockwise direction as viewed in Fig. 1, the clutch connects the 75 crank-shaft 23 with the driving shaft 24 to cause the operation of the press. At the same time the lever 31 breaks the toggle 34 to release the brake. When the shaft 30 is rotated in an opposite direction the clutch is disengaged and the toggle straightened to 80 apply the brake, it being understood that the exact time of application or release of the brake 27 may be varied by adjustment of the clutch and the brake and their operating mechanism.

The operation of the clutch and brake to thereby effect connection or disconnection of the slide and the crankshaft is controlled by a mechanism as will now be described, and embodying an operating handle 40 which 95 when moved to the press starting position 40^a as shown in dotted lines in Fig. 1, moves the link 41 upwardly, this movement being transmitted through the operating shaft 42 to raise the link 43 thereby causing engagement of the clutch and release of the brake 100 and consequent operation of the press. The control mechanism is such that the press may be stopped and started at any point in its cycle of operations by suitable operation of the handle 40, or it may be stopped automatically at a predetermined point in the cycle of operations of the press by trip mechanism 105

operated from the crank-shaft 23 by means of link 44. The present invention embodies means for normally insuring the stopping of the press and the return of the handle 40 even if the operator unintentionally or absent-mindedly retains his hold on the lever 40 so as to hold it in the starting position. Means adjustable by the operator is also provided so that automatic stopping mechanism 16 may be rendered inoperative to permit the continued operation of the press until such time as the operator moves the lever 40 to stop the press.

The control mechanism includes an operating shaft 42 journaled for rotation in a bracket 46 secured to the side of the press. Link 43 is connected between a rearwardly extending lever 47 rigidly secured to one end of the shaft 42 and a rearwardly extending lever 36 rigidly secured on the clutch operating shaft 30. A trip actuated member 48 is keyed to the shaft 42, this member 48 being substantially U-shaped as shown in Fig. 7. The cross-bar of the U provides a forwardly extending head portion 49, and the sides are a pair of spaced apart rearwardly extending arms terminating in lugs 50. Loosely mounted on the operating shaft 42 between the lugs 50 of the U-shaped member 48 is a lever 51 which has lugs 52 and 53 extending from its opposite sides for engagement with the lugs 50 of the member 48. These lugs 52 and 53 are so spaced as to permit a certain amount of lost motion between themselves and lug 50. The control lever 40 is thus connected through a lost motion to the operating shaft 42 since the lever 51 is pivotally connected to the upper end of link 41, the lower end of which connected to a lever 54 on one end of the shaft 55 on which the operating handle 40 is fastened. As shown, a weighted lever 56 is also secured on the shaft 55 to normally urge this shaft and the operating handle 40 towards the right or to press stopping position as viewed in Fig. 1, and consequently tend to maintain it in its normal relationship with operating shaft 42, with the lugs 52 and 50 in engagement.

Loosely mounted on the operating shaft 42 on either side of the trip actuated member 48 are a pair of frames 57 herein shown as of triangular shape which are connected by bolts and spacers as at 59 and 60 to form a cage-like trip carrier. Pivottally mounted on bolt 60 of the trip carrier is a trip or actuated part 61 having a pair of notches or shoulders 62 adapted to engage a face or shoulder 63 formed on the forwardly extending head 49 of the trip actuated member 48. The trip or actuating part 61 is normally held in engagement with the actuated part 48 by means of a spring-pressed plunger 64 which is carried in the boss 65 of the trip carrier 57. The head portion 49 of the trip actuated member carries an unlocking pin 66 which is slidably

mounted in an aperture extending through the head 49 from front to rear, the rear portion being pivoted to a short link 90 the other end of which is pivoted to an upwardly extending lug 67 formed on the lever 51. The unlocking pin 66 is caused to be moved in its aperture by relative movements of the lever 51 and the rock shaft 42 to which the lug 50 is fastened. The trip carrier 57 is connected by means of bolt 59 and rod or link 44 with an eccentrically mounted crank-pin provided on the crank plate 68 secured on the end of the crank-shaft 23. The crank plate 68 is angularly adjustable with respect to the end of the crank-shaft 23, by means of the slots and lock bolts shown in Fig. 2, whereby the position of the trip carrier 57 and the link 44 may be varied with respect to the stroke of the slide 21. At its upper end the trip or actuating part 61 carries a pair of grooved side plates 91 which provide a guide for a slidable block 92 having a top head portion and a depending slide portion. A screw 93 secured in the actuating part 61 and passing through an aperture in the block 92 limits the upward sliding movement of the block and at the same time serves as a central supporting post for the coiled spring 94 which normally holds the block in its uppermost position. Downward sliding movement of the block 92 is limited by engagement of the block itself with the end of the actuating part 61 as illustrated in Fig. 5. The shoulders 62 extend laterally from the side plates 91 for engagement with the shoulder 63 of the trip actuated part. When the block 92 is in its normal uppermost position it will be engaged by the rear end of the unlocking pin 66 when this pin is moved rearwardly, and the actuating part 61 will then be moved about its pivot 60 so that the engagement of the shoulders 62 with the shoulder 63 will be disengaged.

To place the press in operation the operating handle 40 is moved to the starting position 40^a, see Fig. 1. This raises the link 41 and lever 51, whereupon the lug 67 carried by the lever 51 moves the unlocking pin 66 to the right from the position shown in Fig. 4 to push against the slide block 92 of the trip actuating part 61 and thereby swing this actuating part around its pivot 60 and cause the disengagement of the shoulders 62 and the shoulder 63 with which they cooperate. The initial movement of the control lever 40 is thus effective in disengaging the automatic stopping means and permitting the continued operation of the lever 40. On further travel of the lever 51 as the lever 40 continues in its movement towards starting position and after the disengagement of the actuating and actuated parts of the trip mechanism, the lugs 53 engage the lugs 50 on operating shaft 42 so that the latter is rotated in a clockwise direction to the position shown in Fig. 5. The link 43 which is con-

nected to this shaft 42 is thus moved upwardly to ease the engagement of the clutch and the release of the brake, thereby placing the press in operation. Rotation of the 5 crank-shaft of course rotates the crank pin on the plate 68 so that coincidently with the downward movement of the slide 21, the link 44 moves downwardly and swings the trip carrier 57 to the position shown in dotted 10 lines in Fig. 5, while the head 49 of the actuated member remains in the full line position shown in this figure in which position it will be observed, there is considerable space between the lips or shoulders 62 of the actuating 15 part and the shoulder 63 of the actuated part 49. During the upward movement of the slide the link 44 is raised by the crank pin. The trip carrier again swings upwardly carrying with it the actuating part 61, and 20 during the latter part of this upward movement the shoulders 62 of the actuating part engage the shoulder 63 of the actuated part and returns the latter to its initial position as shown in Fig. 4, thereby disengaging the 25 clutch and stopping the press. The preceding sequence of operations take place in the manner indicated if the operator has immediately released the operating handle after he has moved it into the press starting position 40°. Upon its release the operating handle 40 is moved by the weight 56 through a small travel sufficient to restore the lost motion between the lugs 53 and 50, the weight being insufficient however to cause any movement of the operating shaft 42. The weight 56 in urging the lever 40 towards stopping position is therefore effective in causing the retraction of the locking pin 66 since as the 30 lever 51 is moved in a counter-clockwise direction by the weight 56, see Fig. 4, the end of the pin will be withdrawn from the path of the block 92 on the actuating part, and permit the engagement of the shoulders 62 and 63 at the proper time to cause the movement 35 of the operating shaft 42 to press stopping position. The slide member of the press is thus permitted to make one complete cycle of operations as the crank-shaft rotates through 360 degrees, after which the press is 40 automatically stopped at the proper point in its cycle of operations with the slide at the upper portion of its stroke so that access is permitted for insertion and removal of the blank and formed work. If the operator desires to stop the press manually the control 45 mechanism is such that he is permitted to do this at any time in the cycle of operations of the press since movement of the lever 40 to press stopping position is effective through 50 the lugs 52 and 50 to cause the rotation of the operating shaft 42 which is connected to the brake and to the clutch, without interference from the actuating part 61. Similarly 55 he can cause the starting of the press regardless of the position of the trip actuating part

61 since the initial movement of the handle 40 produces a motion of the unlocking pin 66 to disengage the trip actuating part 61 if that part is in the position shown in Fig. 4 in engagement with the actuated part 49. 70

The control mechanism in accordance with this invention is such that if the operator should for any reason retain his hold upon the control lever 40 after it has been moved into the starting position 40°, the automatic 75 trip mechanism will nevertheless cause the stopping of the press at the end of one cycle of operations and cause the return of the control lever to its starting position. This insures that the press will not repeat its stroke even if the operator should absent-mindedly hold the lever 40 in the starting position or fail to release it before the trip actuating part is ready to engage the actuated part of the mechanism. If now the operator holds the operating lever in the starting position 40° after the press has been placed in operation, the trip carrier 57 will carry the trip actuating part 61 downwardly, the spring-pressed plunger 64 holding the trip actuating part 61 to the left in 80 Fig. 4 with the dog 95 held against the stop 96 on the carrier so that the shoulders 62 are in position to engage the shoulder 63 on the trip actuated part; and then upon its return upward movement the upper face of the sliding block 92 will engage the underside of the end of the unlocking pin 66 which pin is still held in its forward or unlocking position projecting from the side of the actuated part 49. However owing to the sliding and yielding 85 support of the block 92 on the trip actuating part 61 the block will slide downwardly as the trip actuating part 61 rises, until the shoulders 62 engage the shoulder 63 on the part 49. The parts will then be in the position as 90 shown in Fig. 5; and then upon continued upward movement of the trip actuating part around the axis of the operating shaft 42 the actuating part will rock the actuated part 48 on the shaft 42 in a counter-clockwise direction to stop the press, at the same time forcibly moving the lever 40 from the starting to the stopping or inoperative position. The weight 56 will then cause the restoration of the lost 95 motion between the lugs 50 and 53 or else the lever 40 may be manually returned to its normal inoperative position to cause the retraction of the unlocking pin 66 and permit the spring-pressed block 92 to move into its normal position as shown in Fig. 4 ready to be 100 engaged by the unlocking pin upon further movement of the press starting lever 40 when the operator again desires to start the press. 105

From the foregoing it will be perceived that the operator cannot maintain the press in operation merely by holding the operating handle in the press starting position, some further and conscious act of the operator being entailed when he desires the press to continue 110 in its operation. The press may however be 115

placed in continuous operation by disengaging or disabling the automatic trip mechanism. This may be done by locking the trip actuating part 61 in an inoperative or ineffective position so that it cannot engage the shoulder 63 of the actuating part. The actuating part is locked in this position so that, although it is moved with the trip carrier 57 as the latter is operated by link 44, it will be held over against the boss 65 and away from head 49 of the trip actuated member and thus be prevented from engaging the latter. The actuating part 61 is so held by means of a locking pin 69, provided on the trip carrier 57, see Fig. 3, which may be turned and permitted to drop under the action of a suitable spring, into a hole 70 formed in the side of the part 61. The dog 95 forms a handle by means of which the trip actuating part 61 may be conveniently lifted so that it may be locked in its inoperative position. When the automatic stopping mechanism is disengaged by holding the spring-pressed actuating part 61 in an inoperative position the press will continue in operation until it is stopped by the operator. The manual control lever 40 may be operated manually at any time in the operation of the press to effect the manual control press.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a power press, a slide member mounted for reciprocation therein, a driving member, a driving connection including clutch means operable when engaged to operatively connect said members and releasable to disconnect said members, manual means including an operating lever operably connected at all times to the driving connection to permit the manual starting and stopping of the press at any time in its cycle of operation, means responsive to the movements of the slide member and automatically operable to engage the driving connection and overcome manual pressure on the operating lever so as to stop the press at a predetermined point in its cycle of operation, and means operated by initial movement of said operating lever towards starting position to disconnect the engagement of said automatically operable means to permit the manual starting of the press.

2. In a power press, a slide member mounted for reciprocation therein, a driving member, a driving connection including clutch means operable when engaged to operatively connect said members and releasable to disconnect said members, manual means including an operating lever operably connected at all times to the driving connection to permit

the manual starting and stopping of the press at any time in its cycle of operation, a rock member responsive to the movements of the slide member and automatically operable to overcome manual pressure on the operating lever so as to stop the press at a predetermined point in its cycle of operation, means operated by initial movement of said operating lever towards starting position to disconnect the engagement of said automatically operable means, and means manually adjustable for disabling said automatically operable means to permit the continued operation of the press.

3. In a power press, a driving shaft, a slide member adapted to be connected with said driving shaft and to be driven thereby, and mechanism for controlling the connection of the slide member with the driving shaft comprising a rock member adapted to be moved into starting position to operably connect the slide member with the driving shaft and to be moved to a stopping position to disconnect the slide member from the driving shaft, a control lever manually operable at any time for controlling said rock member and connected to said rock member through a lost motion, an actuated part concentrically mounted with said rock member, an actuating part connected to said slide to be oscillated as said slide reciprocates, and adapted to engage said actuated part and overcome manual pressure on said control lever to move said rock member and control lever to stopping position at a predetermined time in the cycle of operation, and means operable by the initial starting movement of said control lever for releasing the engagement of the said parts, said parts having provision permitting their effective engagement when the control lever is held in the starting position.

4. In a power press, a drive member, a crank-shaft, a clutch between said drive member and crank-shaft, a brake operating means, a rock shaft connected to the clutch and the brake operating means, a rock member mounted on said shaft, a rod connected to said rock member and reciprocally operable by said crank-shaft, a hand control lever capable of manual operation at any time in the operation of the press to effect the manual starting or stopping of the press, an intermediate control part fast on said shaft and connected through a lost motion to the control lever, a spring-pressed actuating part movably mounted on said rock member, an actuated part adapted to be engaged and moved by said actuating part and mounted on said rock shaft to automatically cause the return of said rock shaft to the stopping position, disengaging means manually adjustable to prevent the engagement of said parts to permit the continued operation of the press, means for normally urging said hand control lever towards the stopping position, the ar-

5 arrangement being such that initial movement of the hand control lever from the stopping position is first effective in causing the disengagement of the actuating and actuated parts to permit the continued operation of the hand control lever for the engagement of the clutch and the release of the brake, said parts having provision permitting their engagement to automatically stop the press
10 when the hand control lever is manually held in the starting position.

5. In a power press, a slide member mounted for reciprocation therein, a driving member, a driving connection including clutch
15 means operable when engaged to operatively connect said members and releasable to disconnect said members, manual means including a single manual operating lever pivotally

mounted on said press for movement in a single plane and operably connected at all times 20 to the driving connection to permit the manual starting and stopping of the press at any time in its cycle of operation, means responsive to the movements of the slide member and automatically operable to engage the 25 driving connection and overcome manual pressure on the operating lever so as to stop the press at a predetermined point in its cycle of operation, and means operated by initial movement of said operating lever towards 30 starting position to disconnect the engagement of said automatically operable means to permit the manual starting of the press.

In testimony whereof I hereto affix my signature.

ARTHUR A. BYERLEIN.
